Specification for Design.

Patented Aug. 9, 1921.

Application filed December 29, 1920. Serial No. 433,945. Term of patent 7 years.

To all whom it may concern:

Be it known that I, JOHN G. BESHARA, a citizen of Syria, residing at Lawrence, in the county of Essex and State of Massachusetts, have invented a new, original, and ornamental Design for Power Hair-Cutters, of which the following is a specification, reference being had to the accompanying drawing, forming part thereof.

Figure 1 is a top plan view of a power hair cutter, showing my new design.

Fig. 2 is a bottom plan view thereof.

Fig. 3 is an elevation as from the bottom of Fig. 2, and

Fig. 4 is an elevation as from the top of Fig. 1.

I claim:

The ornamental design for a power hair cutter, as shown.

JOHN G. BESHARA.
